W. MAUSS,
CENTRIFUGAL DECANTER AND PROCESS.
FILED MAR. 23, 1921.

Inventor

W. Mauss,

FIG I By Marks Clark
Atty.

UNITED STATES PATENT OFFICE.

WILHELM MAUSS, OF JOHANNESBURG, TRANSVAAL, SOUTH AFRICA, ASSIGNOR TO
CONTINUOUS CENTRIFUGALS LIMITED, OF JOHANNESBURG, TRANSVAAL PROV-
INCE OF THE UNION OF SOUTH AFRICA.

CENTRIFUGAL DECANTER AND PROCESS.

Application filed March 23, 1921. Serial No. 454,953.

To all whom it may concern:

Be it known that WILHELM MAUSS, a British subject, residing at 72 Cullinan Buildings, Simmonds Street, Johannesburg, Transvaal, Province of the Union of South Africa, has invented certain new and useful Improvements in Centrifugal Decanters and Processes, of which the following is a specification.

10 The present invention has reference to centrifugal decantation apparatus and is illustrated in the accompanying drawing in which,

15 Fig. I shows a partly sectional view of apparatus according to this invention, and

Fig. II is a plan of the timing apparatus.

Fig. III is a detailed sectional view of the timing barrel.

20 The invention relates more particularly to the invention described in my Patent No. 1419285, granted June 13, 1922.

25 1 indicates a rotating drum formed of a number of sections 2 separable at the surfaces 3. The drum is opened and closed whilst running by mechanism which is fully described in my previous application and need not be detailed here. Said mechanism includes a motor 4 the valve 5 of which is actuated periodically by a tumbling bob 6 which is thrown alternately back and forth by cleats 7 and 8 adjustably fixed on a slowly revolving barrel 9. This barrel is provided with a depending trunnion 9^a which is swiveled in a bracket 9^b. The barrel

30 is connected to the trunnion by a web 9^c and is driven by a worm gearing 9^d. T-shaped grooves 9^e extend around the barrel and in each of these grooves (Fig. III) is mounted an adjustable jaw 9^f held in position by a screw 9^g. The screws are provided with heads or cleats 7, 8, 22, 23, 24 and 25. The drum provides a number of V shaped separating chambers 10, 10^a from which settled solid is discharged into a receiver 11

45 when the drum sections 2 are parted. The material to be treated is fed by a pipe 12 into the drum at one end and the clean liquid is decanted from the other end of the drum through outlets 13 into a receiver 14. The solid matter deposits in the separating chambers 10, 10^a successively from the feed end to the other end of the drum. The separating operation is stopped however before the last separating chamber 10^a is fully charged

with solid in order to preclude solid matter 55 from passing away with the liquid.

In my previous application I showed an additional receiver into which the contents of the last chamber 10^a were discharged, separately from the contents of the chambers 60 10. Provision was made for inspecting such material and either returning the same for re-treatment or adding it to the discharge from the chambers 10 if it were sufficiently separated.

65 According to the present invention after the supply of unseparated material to the decanter is stopped the contents of the chambers 10 and 10^a are washed to displace the original liquid still remaining with the solid. 70 The whole contents of the drum are then discharged into receiver 11 and provision is made for taking a sample of the discharge from the last chamber 10^a.

75 In the drawing 15 indicates a source of supply of say sugar juice, controlled by a valve 16, which discharges into the funnel mouth 17 of the feed pipe 12. 18 is a conduit for supplying wash water which also discharges into the funnel mouth 17 and is 80 controlled by a valve 19. A tumbling bob 20 actuates the juice valve 16, whilst a second tumbling bob 21 actuates the valve 19. The tumbling bobs 6, 20 and 21 are pivotally mounted on suitable supports 6^a. Cleats 22, 85 23, 24 and 25 fixed on the barrel 9 cause the operation of the parts in the following sequence.

80 The drum being revolving and closed, cleat 22 throws the tumbling bob 20 to open 90 the valve 16 whereby impure juice is fed to the drum and separated therein. After a period calculated to enable the lower drum chambers 10 to fill with solid matter and the uppermost chamber 10^a partially to fill 95 therewith, the cleat 23 throws over the tumbling bob 20 to close the valve 16 and at the same time the cleat 24 throws the tumbling bob 21 to open the wash water valve 19. Wash water thereupon flows into the drum 100 from the pipe 12 and displaces the residual sugar juice therefrom. After a sufficient lapse of time to complete such displacement the cleat 7 throws the tumbling bob 6 to actuate the valve 5 of the motor 4 to cause 105 the latter to open the drum whereby the solid matter is discharged. The flow of wash water continues, to assist the discharge

of the solid matter, and is terminated by the cleat 25 throwing the tumbling bob 21 to close valve 19. Immediately thereafter the cleat 8 throws back the tumbling bob 6 to cause the drum to close, whereafter the cycle is repeated.

The various steps enumerated are so timed as to give the greatest economic separation of sugar juice from the solid matter. In order to permit effective control of the timing of the various steps there is provided a sampling device consisting of a pocket 26 fitted on the inside of a door 27 in the wall of the receiver 11. Said pocket is positioned to intercept a small part of the discharge from the chamber 10^a. As said chamber is the least affected by either settlement or washing, if its contents are satisfactory, it is a safe assumption that the lower chambers 10 are also functioning properly. Should too little solid matter be found in the sample, the cleat 22 is set back to prolong the separation period, whilst if the sample indicates an excess of solid matter, so that there is a danger of such matter passing off with the juice, said cleat 22 is advanced. Similarly if underwashing or overwashing is indicated, the cleat 8 is set backwards or forwards accordingly.

30 I claim—

1. The process of centrifugal decantation which consists in centrifugally treating a batch of mixture to cause deposition of solid and decantation of liquid therefrom, fully separating the main portion of the batch and partially separating the remaining portion of the batch, discharging the decanted liquid, displacing residual liquid from the solid by another liquid, and discharging the solid.

40 2. The process of centrifugal decantation which consists in centrifugally treating a

batch of mixture to cause deposition of solid and decantation of liquid therefrom, fully separating the main portion of the batch and partially separating the remaining portion of the batch, discharging the decanted liquid, displacing residual liquid from the solid by another liquid, discharging and sampling the solid of the remaining portion and discharging the solid of the main portion.

3. In a centrifugal decanter, a drum arranged for decantation treatment of mixture, means to feed alternatively mixture and displacement liquid to the drum, a liquid overflow remote from the feeding means, a settlement chamber separate from the rest of the drum and next to the overflow, and means to discharge material from the drum.

4. In a centrifugal decanter, a drum arranged for decantation treatment of mixture, means to feed alternatively mixture and displacement liquid to the drum, a liquid overflow remote from the feeding means, a settlement chamber separate from the rest of the drum and next to the overflow, and a sampling device arranged to receive material discharged from the settlement chamber next to the overflow.

5. In a centrifugal decanter, a drum arranged for decantation treatment of mixture, means to feed alternatively mixture and displacement liquid to the drum, a liquid overflow remote from the feeding means, a settlement chamber separate from the rest of the drum and next to the overflow, a casing forming a receiver for solid matter discharged from the drum, a door in said casing and a pocket arranged on the inside of said door to receive material discharged from the chamber next to the overflow.

In testimony whereof I affix my signature.
WILHELM MAUSS.
